PORTABLE RADIO CABINET

Melvin H. Boldt, Glenview, Ill., assignor to Zenith Radio Corporation, a corporation of Delaware

Filed Dec. 4, 1959, Ser. No. 58,559

Term of patent 14 years

(Cl. D56—4)

FIG. 1

FIG. 2

FIG. 3

FIGURE 1 is a front elevational view of a portable radio cabinet showing my new design;

FIGURE 2 is a reduced perspective view thereof; and

FIGURE 3 is an enlarged fragmentary view of a portion of the grille illustrated schematically in FIGURES 1 and 2.

The left side, not shown, is the same as the right side and the back is unornamented.

The dominant features of my design reside in those portions of the drawings shown by means of full lines.

I claim:

The ornamental design for a portable radio cabinet, substantially as shown and described.
